AUGUST F. H. KOHLER AND ALEXANDER S. SPEER, OF BUFFALO, NEW YORK, AS
SIGNORS, BY MESNE ASSIGNMENTS, TO UNITED STATES GYPSUM COMPANY, OF
CHICAGO, ILLINOIS.

PLASTER BOARD.

Application filed March 2, 1922. Serial No. 540,412.

This invention relates to plaster board or the like and the method of making it.

Among other objects, the invention is intended to provide an improved plaster board, the edge of which is capable of making a close and neat joint with the edge of an adjacent board or the like and which may be easily and inexpensively made.

The invention consists in the novel constructions, combinations and methods, hereinafter described or claimed, for carrying out the above stated object and such other objects as will hereinafter appear.

The invention may be best understood by referring to one illustrative construction embodying the invention, such as that shown, for example, in the accompanying drawing.

In said drawing:

Fig. 1 is a perspective view of portions of adjacent or abutting boards.

Fig. 2 is a transverse section of a board and illustrating also a filled joint between adjacent boards.

Fig. 3 is a transverse section of a board as it appears at one stage of manufacture.

In the drawing, 10 and 11 designate, respectively, what may be termed for convenience, top and bottom cover sheets. Such sheets are preferably of fibrous character, such as paper of the proper quality. Between the cover sheets is a body 12 of plaster or the like to which the cover sheets preferably adhere.

A plaster board of this character may be conveniently made in the ordinary plaster board machine in which a suitable quantity of plaster is deposited on the traveling lower cover sheet, preferably, somewhat wider than the intended width of the board. The top cover sheet, also, preferably, wider than the intended width of the board, is then applied, and the plaster is spread to an even depth, for instance, by passing the cover sheets with the interposed layer of plaster between a pair of spreading rolls which produce a body of plaster of uniform thickness to which the cover sheets firmly adhere.

During the process of manufacture, the margins 13 of the lower cover sheet 11 are turned up so as to form a covering for the edge of the plaster body. The intermediate portions 14 of the margin contacting with the

edge of the plaster body 12 are arranged so that a portion or all thereof is inclined to the plane of the face of the board, or, in the form shown lies inside the vertical planes passing the corners 15 of the board. In the illustrative board, this is effected by inclining or beveling the portions 14 slightly inwardly of the corners 15 of the edges of the board, thereby giving the board a beveled edge. The outer portions 16 of the margins 13 are bent outwardly from the inside edge of the board, substantially parallel to the faces of the board, and are cemented to the projecting margins 17 of the top sheet 10 by any suitable adhesive. Preferably, these margins, 16 and 17, are cemented together by a slight amount of plaster 18 which creeps between the margins during the manufacture of the board.

After the board has been so formed, the margins 16 and 17 are trimmed off if they project farther than is necessary for the edge construction desired. In the illustrative board, the trimmed margins from the corner 19 which does not project substantially beyond a vertical plane passing through the corners 15. This trimming may be effected by suitable trimming knives which are adjusted and arranged to trim off the desired amount.

If desired, in order to form sharp corners at 15 or 20, the cover sheet 11 may be scored along lines representing these corners, in order to weaken the paper along these lines.

In the ordinary use of the board, the sheet 11 forms what is termed the face sheet of the board, that is, this sheet appears on the outer face of the board as it is ordinarily employed in a wall. However, the sheet 10 also presents an unbroken surface, free from joints, and in cases, for instance, where the opposite face of the board is accidentally marred or unsuitable for use as a face sheet, the board may be reversed so that the sheet 10 appears as the face sheet.

In Fig. 1 is illustrated a joint between a pair of abutting boards. The sharp corners at 15 enable the formation of a close and neat joint.

If desired, in order to entirely obliterate these joints without the use of strips of material, they may be filled, as illustrated in

Fig. 2, with a suitable joint filler. The cavity 21 formed by adjacent margins 14 is filled with plaster or other filler, forming a key 22 which keeps the entire filling in place.

Obviously the invention is not limited to any particular construction, and the details of the illustrative board may be variously modified. Moreover, it is not indispensable that all features of the invention be used conjointly, as they may be used to advantage in various different combinations and sub-combinations.

Having thus described our invention, we claim:

1. A plaster board or the like comprising, in combination, a layer of material forming the body of the board having an edge thereof beveled, and covering material enveloping said body and adhering thereto, the edges of said material substantially meeting at the inside of the bevel of said edge and one of said edges projecting outwardly from the edge of said body.
2. A plaster board or the like comprising, in combination, a layer of material forming the body of the board having an edge thereof beveled, and covering material enveloping said body and adhering thereto, the edges of said material substantially meeting at the inside of the bevel of said

edge and projecting outwardly to a point flush with the outer edge of said bevel.

3. A plaster board or the like comprising, in combination, a layer of material forming the body of the board having the side edges thereof inclined within the normal plane of the edge of the body, covering material enveloping and adhering to said body, the edges of said material meeting at the inner end of said inclined edges and projecting outwardly from the edge of said body, said projecting edges capable of being trimmed off as desired to make the finished edge of the board.

4. A plaster board comprising in combination, a relatively rigid board-like body of plaster having a plurality of covering sheets adhering to the faces thereof and adhesively reinforcing the body from edge to edge, said plaster body being formed with side edges each of which lies wholly in a plane inclined to the face of the board the said covering sheet substantially meeting at the inner edge of the bevel and extending outwardly substantially flush with the outer edge.

In testimony whereof we have signed our names to this specification.

AUGUST F. H. KOHLER.
ALEXANDER S. SPEER.
